UNITED STATES PATENT OFFICE.

AUGUSTUS J. SIGRIST, OF HIGHLAND PARK, ILLINOIS, ASSIGNOR TO WILLIAM J. RANKIN, OF CHICAGO, ILLINOIS.

DISPLAY STAND AND THE LIKE.

Application filed July 20, 1927. Serial No. 207,122.

This invention has to do with improvements in display stands and the like. More particularly, it has to do with improvements in display stands of the easel type intended 5 to be stood on show cases, tables, counters, display windows and other advantageous locations.

One of the objects of the invention is to provide a device of the foregoing character 10 which is of such a construction that certain portions of the displayed material may be brought into a perspective or relief position with respect to other portions thereof so that they will be made to stand out and be displayed more advantageously and to better 15 advantage. This feature of the invention is accomplished by providing a construction such that certain portions of the display may be actually physically set forward or in advance of other portions thereof.

Another feature of the invention relates to the provision of a device capable of producing the foregoing results, which device may be flattened out into a single plane so that 20 it can be readily shipped in bundles or packages; but which device is also so constructed that the user can readily fold it around into the desired form to establish the perspective and display usage.

25 A further object in connection with the foregoing is to provide an arrangement such that a desirable form of easel will be established to sustain the complete device in upright position on the table or other support. 30 This easel is so constructed that it may be readily turned out into the working position or may be folded back against the back surface of the article.

35 A further object of the invention relates to the provision of an arrangement whereby the perspective display may be established by means of a background of conical form with its convex surface facing the observer; the article which is to be most prominently 40 displayed being presented at the central portion of said conical surface so as to emphasize the presence thereof.

45 A further object of the invention relates to the provision of a construction embodying all of the foregoing features, and which is so arranged that when made in relatively 50 large sizes it can be readily folded up into a smaller and more compact space of substantially half size so as to facilitate shipment in smaller packages.

Other objects and uses of the invention will appear from a detailed description of the same, which consists in the features of construction and combinations of parts hereinafter described and claimed.

60

In the drawings,—

Fig. 1 shows a front face view of a display stand opened out into the normal condition for use, the particular form illustrated in the drawings including the face of a young man which is prominently displayed at the apex of a conical, circular surface established around his head; this figure also shows by dotted line the normal position of the upper display section when the same is flattened out into shipping condition;

Fig. 2 shows a cross section on the line 2-2 of Fig. 1, looking in the direction of the arrows;

Fig. 3 shows a back view of the entire stand in its flattened-out form before it is folded around into the display condition, the easel being folded down into shipping position; and

Fig. 4 shows a back perspective view corresponding to Fig. 1, the parts being folded around into their normal working position.

Referring first to Fig. 1, in the construction therein illustrated, I have chosen to show the face of a young man 6 as being prominently displayed or emphasized by the presence of a conical background 7 established immediately behind the face and head, which are to be most prominently displayed. Both the face 6 and background 8 are supported above a base portion 9, which in the form illustrated includes an arbitrary rectangular section 9 such as might be used for advertising a tube of tooth paste or some similar article of merchandise.

The background 7 is of generally circular form, and, as will be clearly seen from Fig. 2, it comprises a paper or cardboard section which is dished or convex in form so as to present a forwardly-facing convex surface. It will also be noticed that the face and head section 6 is displayed substantially at the center or cone portion of this conical background. By reason of this arrangement, the appearance and position of the head and face are greatly emphasized, and they are caused to stand out with remarkable prominence against the background 7. In fact, the naturalness of this

display is not readily appreciated merely from a pictorial illustration, and can only be properly understood and appreciated by an examination of an actual construction embodying this feature.

In order to still further enhance the perspective display just referred to, I prefer to place one or more circular or corona lines 10 around the front surface of the background 7 and substantially concentric with the display element 6; and the effect is still further improved by gradually shading the color of the background 7 from a very dark or deep condition in its central portion to 15 a much lighter tone in its border or peripheral portion. This shading and coloring, which is partially illustrated by the shading of the drawing in Fig. 1, tends to enhance the appearance of distance in the central portion of the background so that the figure 6 is made to stand forward much more prominently.

The parts 6, 7, 8 and 9 may all be made as a single unit or blank of the form illustrated in Fig. 3. This is done by cutting on the line 11 between the figure 6 and the background 7, so that these parts are severed commencing substantially at the point 12. The parts 8 and 9 are simply cut out to the proper shape for the lower or base portion, as will be readily understood from Fig. 3. Preferably also the blank is cut of proper size to establish a lug 13 along the lower portion, and a folding line 14 is established so as to facilitate folding said lug backwardly into the position shown in Fig. 4.

The crescent-shaped background 7 terminates at the point 15 and is provided with a hook member 16 having the downwardly extending lug 17 which can be hooked into a suitable notch or slot to receive the same when the crescent-shaped background 7 has been pulled around as will now be explained:

When it is desired to establish the cone-shaped background from the crescent-shaped member 7, the lower portion 15 thereof is pulled around and behind the section 6, as will be readily understood from Fig. 4, wherein the edge 11 of the crescent background member 7 appears to overlie the back surface of the member 6. This bending operation is continued until the desired amount of cone has been established; and preferably the parts should be so proportioned that this will occur when the hook 16 has been drawn over substantially to the meeting line of the stand. Any suitable notched or slotted device may be provided for receiving the hook 17, but in the construction illustrated I make use of the easel itself for this purpose.

The easel 18 includes a lug 19 which is secured to the back surface of the lower

portions 8 and 9, and also includes a wing 20 which may be folded out at right angles to give the desired support. The lower edge 21 of this wing 20 is cut at the proper angle to sustain the device in the desired upright position, and said wing 20 is also notched at the point 22 to receive the lug 13 already referred to.

An ear 23 is cut out from the material of the easel member 18 and across the folding line 24 thereof, so that when the member 20 has been turned out at right angles, as shown in Fig. 4, this ear 23 can then be turned down into the position of Fig. 4. This ear 23 is also provided with a notch 25 adapted to receive the edge of the member 20 so as to hold the same in the position of Fig. 4.

The easel member 18 is also provided with a slot 26, preferably formed substantially along the folding line 24, which slot is in the proper position to receive the lug 16 when the crescent-shaped member 7 has been drawn around into the position of Fig. 4.

The display stand herein illustrated is of relatively large size and is provided with a folding line 27 which reaches across its central portion in an upwardly slanting direction. The easel member 18 is also provided with a folding line 28 somewhat below the position of the folding line 27, and near the lower portion of the lug 19 below the folding line 28 is permanently secured to the back face of the stand. As a consequence, when the wing 20 of the easel member 18 is laid over flat against the back surface of the display member, the upper portion of the easel member 18 may be folded down into the position of Fig. 3.

When the device is to be used, the easel member is first unfolded and raised up to its full height, and then the wing 20 is turned out at right angles and locked in the position of Fig. 4. In order to retain the easel member solidly in this position, I have provided an oblong opening 29 in the upper portion of the lug 19, and have also provided a locking wing 30 pivoted to the back face of the member 6 at the point 31. When the easel member is raised up into the position of Fig. 4 the locking member 30 passes through the opening 29 and may then be turned over at right angles, as shown in Fig. 4, so as to lock these parts together. If necessary, a slot 32 may be provided in the upper portion of the wing 20 to receive this locking member when so turned into the working position.

While I have herein shown and described only a single embodiment of the features of my present invention, still I do not intend to limit myself thereto except as I may do so in the claims.

I claim:

1. As a new article of manufacture, an advertising novelty comprising a cardboard sheet having its lower portion of suitable

- contour and finish to establish a base member, an upwardly reaching central display element which is to be most prominently displayed, upwardly projecting from said base member, a substantially circular corona element encircling the central display element aforesaid and having one end integrally connected to the lower portion of one side of the central display element and having its major portion disconnected from the central display element, whereby the free end of said corona element may be drawn downwardly and inwardly behind the central display element and be thereby caused to assume a conical form with its concave surface facing forwardly and behind the central display element, means for securing said free end in such position, circular shading on the front surface of said corona element, said shading being relatively dark in the central portion as compared to the peripheral portion thereof, and a suitable bracket stand in conjunction with said device, substantially as described.
2. As a new article of manufacture, an advertising display novelty comprising a pasteboard or cardboard base member, a central display element extending upwardly therefrom, a substantially circular corona element encircling said central display element and having one end integrally connected to the lower portion of one side of the central display element and having its free end adapted to be drawn down and inwardly behind the central display element to thereby cause the corona element to assume a conical form with its concave surface facing forwardly and behind the central display element, the front surface of the corona element being shaded and of darker appearance in its central portion than in its peripheral portion, means for securing the free end of the corona element in such position, and a suitable bracket member in conjunction with said device, substantially as described.
3. As a new article of manufacture, an advertising display novelty comprising, in combination, a base member, a central display element projecting upwardly therefrom, a substantially circular corona element surrounding the central display element and having one end rigid with respect to the lower portion of one side of the central display element, whereby the free end of the corona element may be drawn downwardly and inwardly behind the central display element to thereby cause the corona element to assume a conical form with its concave surface facing forwardly behind the central display element, means for securing the corona element in such position, and a suitable bracket member in conjunction with said device, substantially as described.
4. As a new article of manufacture, an advertising display novelty comprising, in combination, a base member, a central display element projecting upwardly therefrom, a substantially circular corona element surrounding the central display element and having one end relatively movable towards each other, whereby when said ends are drawn towards each other and behind the lower portion of the central display element the corona element is caused to assume a conical form behind the central display element and with its concave surface facing forwardly, to thereby enhance the prominence of the display of the central display element, means for securing the corona element in such position, and suitable bracket devices for supporting the device in upright position, substantially as described.
5. As a new article of manufacture, an advertising novelty comprising, in combination, a unitary blank of cardboard or pasteboard having its lower portion cut to the perimeter of a desired base member and having its upper portion cut to the perimeter of a substantially circular corona element above the position of the base member, and also being provided with a cut line defining the perimeter of the major portion of a central upwardly projecting display element, to thereby disengage the corona element from the central display element along such line and permit the free end of the corona element to be drawn downwardly and inwardly behind the position of the central display element to thereby establish a conical corona member behind the central display element and with its concave surface facing forwardly, means for securing the free end of the corona element in such position, and a suitable bracket in conjunction with all of said parts, substantially as described.
6. As a new article of manufacture, an advertising display novelty comprising, in combination, a base member having an upwardly projecting central display member on its upper portion, all of said parts normally lying in substantially the same plane, a substantially circular corona element encircling the central display element and located behind the same with its concave surface facing forwardly, one end of said corona element being rigid with respect to the central display element, a bracket stand on the back surface of the base member and projecting rearwardly therefrom, there being a substantially vertical slot in said bracket member immediately adjacent to the back surface of the base member, and a suitable hook on the lower portion of the free end of the corona element adapted to engage said slot to thereby secure the corona element in conical form and with its free end lying close to the back surface of the base member, substantially as described.
7. As a new article of manufacture, an

advertising novelty for the purpose specified comprising, in combination, a base member having an upwardly projecting central display element, both of said parts lying substantially in the same plane, a substantially circular corona element surrounding the central display element and of conical form, with its concave surface facing for-

wardly, one end of said corona element being rigid with respect to the central display element, and means for securing the free end of the corona element rigid with respect to the central display element and in close proximity to the back surface of the base member, substantially as described.
